CIRCUIT CONTROLLER

William E. Smith, Pittsburgh, Pa., assignor to
The Union Switch & Signal Company, Swiss-
vale, Pa., a corporation of Pennsylvania

Application January 29, 1937, Serial No. 123,014

12 Claims. (Cl. 177—311)

My invention relates to circuit controllers, and particularly to circuit controllers adapted for assembly on a control panel as one of a compact group of similar units for controlling railway switches and signals or other apparatus.

One object of my invention is to provide a circuit controller of the type described having associated therewith indication means for indicating the condition of the device or devices controlled by the circuit controller.

Another object of my invention is to provide a circuit controller of the type described, which will not only have a compact, accessible, and reliable type of construction, but which at the same time may be constructed at a minimum cost.

Circuit controllers embodying my invention are particularly suitable for, although in no way limited to, use in connection with railway traffic controlling apparatus of the type disclosed and claimed in an application for Letters Patent of the United States, Serial No. 118,609, filed by John M. Pelikan, on December 31, 1936.

I will describe several forms of circuit controllers embodying my invention, and will then point out the novel features thereof in claims.

In the accompanying drawings, Fig. 1 is a top plan view, partly in elevation and partly in section, showing one form of circuit controller embodying my invention. Fig. 2 is a vertical longitudinal sectional view of the circuit controller shown in Fig. 1. Fig. 3 is a detail view showing the construction of one of the stacks of contacts forming part of the circuit controller shown in Figs. 1 and 2. Fig. 4 is an end view of the circuit controller shown in Figs. 1 and 2 as it appears when viewed from the right in Fig. 1. Fig. 5 is a top view, partly in section and partly in elevation, showing another form of circuit controller embodying my invention. Fig. 6 is a vertical longitudinal sectional view of the circuit controller shown in Fig. 5. Fig. 7 is a top view, partly in section and partly in elevation, showing a third form of circuit controller embodying my invention. Fig. 8 is a side view, partly in elevation and partly in section, of the circuit controller shown in Fig. 7. Figs. 9 and 10 are sectional views taken on the lines IX—IX and X—X, respectively, of Fig. 7. Fig. 11 is an end view of the circuit controller shown in Figs. 7 and 8 as it appears when viewed from the right in Fig. 7. Fig. 12 is a view, partly in side elevation and partly in section, showing a fourth form of circuit controller embodying my invention. Fig. 13 is a view similar to Fig. 12 showing a modification of the circuit controller illustrated in Fig. 12.

Similar reference characters refer to similar parts in each of the several views.

Referring first to Figs. 1 and 2, the circuit controller in the form here shown comprises a

suitable framework consisting of a front support 1 secured, by means of flat-headed screws 2, to the forward end of a base plate 3, and a rear support 4 secured, by means of flat-headed machine screws 5, to a tail-like extension 3a of the base plate 3, the heads of the screws 2 and 5 being made flush with the under side of the base plate for a purpose which will become apparent as the description proceeds. The front support 1 is formed with a reamed hole 1a surrounded at its forward end by a boss 1b, and the rear support 4 is formed with a screw-threaded hole 4a which aligns axially with the hole in the front support 1.

The hole 1a in the front support 1 slidably receives a tubular operating member 6, the inner end of which is screwed into a split collar 7a forming part of a rectangular housing 7 which comprises part of a light unit U. The collar 7a is provided with two laterally projecting lugs which may be drawn together by means of a screw 8 to lock the operating member in place in the collar. The operating member normally occupies the position shown, but is adapted to be at times pushed inwardly to one extreme position, and at other times pulled outwardly to another extreme position, to effect the operation of the contacts of the circuit controller, as will be described more fully hereinafter, and to facilitate grasping the operating member 6, the outer end of the operating member is formed with an integral button 6a.

Extending through the operating member 6 from one end thereof to the other is a clear glass rod 6b which is adapted to be at times illuminated by light rays from one or the other of a pair of indication lamps 9 and 10 that are disposed within the housing 7 of the light unit U, to give to the operator of the circuit controller an indication of the position or condition of the signal or other device which is controlled by the circuit controller. In order that the indications given may be clearly and readily distinguishable from each other, the two lamps may be provided with differently colored bulbs to cause differently colored light rays to be transmitted from the lamps to the rod, or the inside of the housing 7 may be divided into two compartments by means of a partition wall 11 and two differently colored filters 12 and 13 in such manner that a different one of the filters will be disposed between each bulb and the rod, this latter construction being shown in Fig. 1. It will be obvious, of course, that when differently colored filters are provided, lamps having uncolored bulbs may be used. In actual practice, the two indications will usually be red and green to correspond with standard signaling practice, although this particular arrangement is in no way essential to my invention. The indication lamps 9 and 10 are mounted

in lamp sockets 14 and 15 which sockets, in turn, are mounted in suitable openings provided in a metal plate 16 secured to an insulating lamp supporting bracket 17 having formed therein the openings which align with the openings in the plate 16. The bracket 17 is U-shaped, and the legs thereof are secured to the opposite sides of the housing 7 by means of flat-headed machine screws 18. The rear end of the housing 7 is open, and the parts are so proportioned that sufficient room is provided between the housing 7 and the yoke of the lamp supporting bracket 17 to allow for adequate ventilation. The lamp sockets may be of any suitable type, but are preferably of the J-slot or bayonet type which can be locked in place by pushing them inwardly in the associated openings in the plate 16 and bracket 17, and then rotating the socket to another angular position. Sockets of this type are in widespread commercial use, and a detailed description of these sockets is therefore believed to be unnecessary. Electrical connection with the one terminal of each lamp is made through the shell of the associated socket 14 or 15, the metal plate 16, and a wire 19 which is soldered to the plate 16. Electrical connection with the other terminal of the lamp 9 is made through the usual spring biased member 14^a of the associated socket 14 and a wire 20 which is electrically connected to this member; and electrical connection with the other terminal of the lamp 10 is made through the usual spring biased member 15^a of the associated socket 15 and a wire 21 which is electrically connected to the member 15^a.

The circuit controller also comprises a metal plate 22, one end of which is secured to the under side of the housing 7 of the light unit U by means of machine screws 23 having flat heads which are flush with the under side of the metal plate 22, and the other end of which is secured to a spring basket 24 forming part of a device D for biasing the operating member 6, the housing 7, and the metal plate 22 to the position shown in such manner that these parts may be moved in opposite directions from the position shown through the medium of the operating member 6.

The biasing device D may have any preferred construction, but in the form here shown this device comprises, in addition to the spring basket 24, two sleeves 25 and 26, a spring bolt 27, and a compressed coil spring 28. The spring basket 24 comprises a rigid metal strip bent to form a yoke portion 24^a to which the plate 22 is riveted, and two inverted L-shaped portions the vertical legs 24^b and 24^c of which are disposed at right angles to the yoke portion 24^a, and the horizontal legs 24^d and 24^e of which extend parallel to the yoke portion in offset spaced plane relation thereto. The legs 24^b and 24^c are provided with holes 24^f and 24^g which align axially with the hole 1^a in the front support 1 of the frame, and the hole 4^a in the rear support 4; while the legs 24^d and 24^e are provided with holes 24^h and 24ⁱ. The sleeves 25 and 26 are slidably mounted in the holes 24^f and 24^g, respectively, and are provided at their confronting ends with annular flanges 25^a and 26^a, respectively. The spring bolt 27 is provided adjacent its head with an enlarged shank portion 27^a which is screwed into the hole 4^a in the support 4, and the main part of the shank of this bolt extends with some clearance through the two sleeves 25 and 26, and is provided at its free end with a stop nut 29 and a jam nut 30. The compressed coil spring 28 surrounds the spring bolt 27 between the two sleeves 25 and

26, the parts being so proportioned that the spring will hold the sleeves in the position in which their flanges engage the associated legs 24^b and 24^c, and that when these flanges are engaging the legs 24^b and 24^c, the outer end of the one sleeve will engage the front vertical face of rear support 4, and the outer end of the other sleeve will engage the stop nut 29. A lock washer 31 is interposed between the head of the spring bolt and the rear support 4 to lock the spring bolt in place in the support.

With the biasing device D constructed in the manner shown, it will be apparent that upon pushing the operating member 6 inwardly a force will be transmitted to the spring 28 through the housing 7, the plate 22, the spring basket 24, and the sleeve 25, which force will compress the spring 28 beyond its initial compression, and that, as a result as soon as the operating member is released the spring will act to immediately return the parts to the positions shown. Likewise, upon pulling the operating member 6 outwardly, a force will then be transmitted to the spring 28 through the housing 7, the plate 22, the spring basket 24, and the sleeve 26, which force will also compress the spring beyond its initial compression, with the result that as soon as the operating member is released, the spring will again act to immediately return the parts to the positions shown. It will also be apparent that the extreme position to which the parts can be moved in one direction is limited by engagement of the leg 24^c of the spring basket 24 with the rear support 4, whereas the extreme position to which the parts can be moved in the other direction is limited by engagement of the split sleeve 7^a with the rear face of the front support 1 of the frame.

Secured to the legs 24^d and 24^e of the spring basket 24 by means of screws 35 which are screwed into the holes 24^h and 24ⁱ is a channel-shaped wire guide 33 of insulating material, which guide supports the wires 19, 20, and 21 leading to the light unit U. The wires are held in place within the guide by a strip 37 of insulating material, which strip extends transversely of the guide adjacent to its right-hand end directly above the wires, and which is secured to the guide by a bolt 38. The guide extends rearwardly past the rear support 4, and serves to prevent the wires from becoming worn due to repeated operation of the circuit controller.

The circuit controller further comprises a plurality of groups or stacks of contacts, here shown as two in number and designated by the reference characters S¹ and S², respectively. These stacks are secured to insulating strips 40 and 41 which extend rearwardly from the base plate 3 of the frame on opposite sides of the rear support 4, and are similar in construction so that a description of one will suffice for both. Referring particularly to the stack S¹ shown in detail in Fig. 3, this stack comprises a plurality of superposed blocks 42^a, 42^b, etc., of insulating material attached to the strip 40 by means of screws 43. A first movable contact finger 44 is clamped between the two blocks 42^a and 42^b, and the outer end of this finger is provided with a downwardly projecting return bend 44^a, the function of which will be made clear presently. A fixed contact finger 46 is clamped between the blocks 42^b and 42^c, and is retained in its normal position by a relatively stiff metal stop 47 which is also clamped between the same two blocks. A second movable contact finger 48 is clamped between the

blocks 42^c and 42^d, and the free end of this finger is bent downwardly at right angles at 48^a. A small plate 49 of insulating material is attached to the bent end 48^a and is adapted to engage with the free end of the movable finger 44. A second fixed contact finger 50 is clamped between the blocks 42^d and 42^e, together with a metal stop 51 which is arranged to limit the downward movement of the finger 50. The fingers are so adjusted that when no upward thrust is exerted on the movable fingers 44 and 48, the parts will occupy the positions shown, in which positions the movable fingers are out of engagement with the associated fixed fingers 46 and 50. The screws 43 are insulated from the various fingers and strips by means of insulating bushings 52 which surround the screws.

The return bends 44^a on the contact fingers 44 of the two stacks S¹ and S² of contacts cooperate with an insulating cam 55 which is secured to the movable plate 22. This cam is formed with a high portion 55^a, and with two low portions 55^b and 55^c so arranged that the return bend 44^a on the finger 44 of the stack S¹ will ride on the low portion 55^b except when the operating member is pushed inwardly to its right-hand or inner extreme position, at which time the return bend will ride up onto the high portion, and that, the return bend 44^a on the finger 44 of the stack S² will ride up onto the high portion 55^a except when the operating member 6 is pulled outwardly to its left-hand or outer extreme position, at which this return bend will move off of the high portion onto the low portion 55^c. The parts are so proportioned that when the return bend 44^a on the finger 44 of either stack is engaging the high portion 55^a of the cam, the finger 44 of such stack will be forced upwardly to the position in which it engages the associated fixed contact finger 46 to close the contact 44—46, and the finger 48 of such stack will be forced upwardly by engagement of the member 49 with the associated finger 44 to the position in which the finger 48 engages the associated fixed contact finger 50 to close a contact 48—50, but that, when the return bend 44^a on the finger 44 of either stack is engaging the associated low portion 55^b or 55^c of the cam, the fingers 44 and 48 of such stack will be permitted to move downwardly due to their inherent bias to the position in which the contacts 44—46 and 48—50 of such stack are opened.

The circuit controller is intended to be secured to a control panel such as the control panel 56 shown in the drawings in such manner that it can readily be removed for inspection or repair, and to this end an L-shaped mounting bracket 57 is provided. This bracket is secured to the rear face of the control panel by means of rivets which pass through the panel and through the vertical leg 57^a of the bracket, and formed in the vertical leg in the bracket is a hole 57^b which aligns with a hole 56^a in the panel, the two holes 57^b and 56^a being of sufficient diameter to receive the button 6^a of the operating member 6 and the boss 1^b of the front support 1 with some clearance. The circuit controller is mounted on top of the horizontal leg of the bracket 57 with the bushing 1^b and operating member 6 projecting through the holes 57^b and 56^a, and is secured to the bracket by means of a machine screw 58 and the dowel effect provided by the bushing 1^b on the support 1. The machine screw 58 passes through a hole 4^b in the rear support 4, and is screwed into a tapped hole 57^d provided

in the tail-like extension 57^c of the horizontal leg of bracket 57, and it will be apparent that in order to remove the circuit controller from the panel, it is only necessary to remove the machine screw 58, and then slide the control panel rearwardly to the point in which the operating member 6 is clear of the holes 57^b and 56^a.

The operation, as a whole, of the circuit controller is as follows: When the operating member 6 is released, all parts occupy the positions in which they are shown in the drawings, and under these conditions the contacts 44—46 and 48—50 of the stack S¹ are open and the corresponding contacts of the stack S² are closed. When, however, the operating member 6 is pulled outwardly, the light unit, plate 22, and cam 55 all move toward the left in opposition to the bias of the biasing device D, and under these conditions, the contacts 44—46 and 48—50 of stack S² become opened and the corresponding contacts of stack S¹ remain open. Upon releasing the operating member, the biasing device D will automatically restore the operating member, the light unit U, plate 22, and cam 55 to the position shown and the contacts of stack S² will return to their normally closed positions. If the operating member is pushed inwardly, the light unit, plate 22, and cam 55 will all move toward the right in opposition to the bias of the biasing device D, and the contacts 44—46 and 48—50 of stack S² will remain closed, and the corresponding contacts of stack S¹ will become closed. Upon releasing the operating member, the parts will again immediately return to the position shown. When the device controlled by the circuit controller has responded to the operation of the circuit controller, one or the other of the indication lamps will become lighted, thus causing the outer end of the operating member to become illuminated, and hence giving the operator an indication of the fact that the device controlled by the circuit controller has responded. The means for controlling the indication lamps form no part of my present invention and are therefore not shown in the drawings.

Referring now to Figs. 5 and 6, the operating member 6, the light unit U, and the mounting bracket 57 of the circuit controller here shown are all similar in construction with the correspondingly designated parts of the circuit controller shown in Figs. 1 and 2. The operating member 6 of the circuit controller, however, is slidably mounted in a bushing 62 which is riveted to the vertical leg 69^a of an L-shaped plate 60, and which bushing projects through the hole 57^b in the vertical leg 57^a of the bracket 57 and the aligned hole 56^a in the control panel 56. The horizontal leg 60^b of the plate 60 rests on the horizontal leg 57^c of the bracket 57, and is secured thereto by means of a pair of screws 61, the plate 60 being positioned at its forward end by the dowel effect produced by the bushing 62.

The operating member 6 and light unit U are biased to the position shown by a biasing device D¹, the rectangularly shaped housing 64 of which is operatively connected with the housing 7 of the light unit U through the medium of a plate 22^b secured to both housings. The biasing device D¹ differs somewhat from the device D shown in Fig. 1, and comprises a spring bolt 65 which is mounted at one end in a block 66 secured to the leg 60^b of the plate 60 by means of screws 67. The other end of the spring bolt projects through aligned openings 64^a and 64^b formed in the opposite end walls of the housing 64. A lock nut 68

is provided on the spring bolt 65 adjacent the block 66, and slidably mounted on this spring bolt adjacent this nut is a bushing 69 which projects into the housing through the opening 64^b and is provided on the inside of the housing with an annular flange 69^a. The spring bolt is also provided with a washer 70 which is slidably mounted on the bolt within the housing 64, and with a compressed coil spring 72 which surrounds the spring bolt between the washer 70 and the flange 69^a of the bushing 69, and which spring urges the washer 70 to the position in which it engages the associated end wall of the housing, and the bushing 69 to the position in which the flange 69^a engages the associated end wall of the housing. Upon pushing the operating member 6 inwardly from the position shown, the spring 72 is compressed through engagement of the end wall of the housing with the washer 70, and upon removing the force from the operating member, the operating member and housing will be restored to the position shown by the spring, this position being determined by engagement of washer 70 with the head of the spring bolt 65 and by engagement of the bushing 69 with the lock nut 68. Upon pulling the operating member outwardly from the position shown, the spring 72 is again compressed through engagement of the flange 69^a with the end wall of the housing, so that as soon as the operating member is released, the parts will immediately return to the positions shown.

The contacts of the circuit controller are mounted on top of the block 66, and are operated by a cam 74 secured to the top of the housing 64 of the biasing device. Only two contacts are provided, and each of these contacts comprises a movable finger 44 and a fixed finger 46 clamped between superposed insulating blocks 42^a, 42^b, and 42^c in a manner similar to that shown in Fig. 1. The cam 74 is similar to the cam 55 previously described in connection with Fig. 1, and comprises a high portion 74^a and two low portions 74^b and 74^c. The parts are so proportioned that when the operating member occupies the position shown, the return bend 44^a on the one movable contact finger 44 will engage the cam 74 at the high portion and the return bend 44^a on the other finger 44 will engage the cam at the low portion 74^b, and under these conditions the one contact 44-46 will be closed and the other contact will be open. When, however, the operating member is pushed inwardly to its one extreme position, the return bend 44^a on the one finger will remain on the high portion 74^a of the cam and the return bend on the other finger will ride up onto the high portion, thus causing the one contact to remain closed and the other contact to become closed. Conversely, when the operating member is pulled outwardly to its other extreme position, the return bend 44^a on the one contact finger will ride off of the high portion 74^a and onto the low portion 74^c of the cam 74, and the return bend 44^a on the other finger 44 will remain on the associated low portion, thus causing the one contact to become opened and the other contact to remain open. It will be obvious, of course, that when the operating member is released following its movement to either extreme position, it will immediately be returned to the position shown due to the bias of the biasing device D¹, and the contacts of the circuit controller will immediately be restored to their normal positions in which the one contact is closed and the other contact is open. The inner posi-

tion to which the operating member 6 can be pushed is limited by engagement of the inner end of the plate 22^b with the block 66, and the extreme position to which the operating member can be pulled is limited by engagement of the sleeve 7^a with the vertical leg 60^a of the plate 60.

It will be noted that with the circuit controller constructed in the manner shown in Figs. 5 and 6, it can be removed from the panel by removing the screws 61 and then sliding the circuit controller rearwardly away from the panel to the position in which the operating member 6 is clear of the opening 57^b in the vertical leg of the bracket 57.

Referring now to Figs. 7 and 8, in the form of circuit controller here shown a mounting plate 80 having an opening 80^a therethrough that is somewhat larger than, but aligns with, an opening 56^a in the control panel 56, is secured to the control panel 56 as by rivets 81. The rivets 81 have heads which are made flush with the front surface of the panel in order to render the front surface of the panel smooth, and with the rear surface of the plate in order to enable the plate to receive in flat surface relation thereto a front support 82^a comprising part of a frame 82. The front support is clamped against the plate 80 by means of bolts 84, and is formed with a stepped tubular portion 82^b which accurately fits the opening in the plate 80 and the opening 56^a in the control panel 56. Extending through the tubular portion 82^a is a reamed hole 82^c which slidably receives a tubular operating member 85, the outer end of which is provided with a bull's eye 86. The bull's eye is adapted to be at times illuminated by indication lamps 87 and 88 disposed within a housing 89 which is secured to the rear end of the operating member and which forms part of a light unit U¹. The lamps 87 and 88 are disposed in sockets 14 and 15 mounted in a plate 16 secured to an insulating lamp supporting plate 90, which latter plate, in turn, is secured to the rear end of the housing 89 by means of screws 91 in the manner shown in Figs. 7 and 10. Connections to the lamp sockets 14 and 15 are made in the same manner as in Figs. 1 and 2.

The frame 82 includes, in addition to the front support 82^a, an arm 82^d which extends normal to the front support at the top thereof, and an integral housing 82^e which houses a biasing device D². The biasing device D² in the form here shown comprises a spring rod 92 provided adjacent one end with an enlarged portion 92^a and at the other end with a head 93 which is pinned to the spring rod. The enlarged portion 92^a is slidably supported in a bearing 82^f formed in one end of the housing 82^e, while the head 93 is slidably supported in a bearing sleeve 94 which is screwed into the other end of the housing 82^e. Surrounding the spring rod within the housing are two washers 95 and 96 which are free to slide relative to both the spring rod and the housing, and a compressed coil spring 97 which biases the washer 95 to the position in which it engages a shoulder 82^g formed at the inner end of the bearing 82^f, and the washer 96 to the position in which it engages the inner end of the bearing sleeve 94. The parts are so proportioned that when the washer 95 is engaging the shoulder 82^g, and the washer 96 is engaging the bearing sleeve, the washer 95 will also engage a shoulder 92^b formed on the spring rod 92 at the inner end of the enlarged portion 92^a, and the washer 96 will engage the inner end of the head 93. It will be seen, therefore, that movement of the spring rod

away from the position shown in either direction will compress the spring 97 beyond its initial compression, and that, as a result, as soon as the force which moved the spring rod is removed, the spring will act to immediately restore the spring rod to the position shown.

The spring rod 92 is secured at its forward end to an L-shaped extension 89^a of the housing 89 of the light unit U¹, and acts both as a means for slidably supporting the light unit and also as a means for operatively connecting the light unit and the operating member with the biasing device.

A circular flange 93 is formed on the rear end of the spring housing 82^e, and secured to this flange by means of screws 99 (see Fig. 11) is a terminal board 100 of suitable insulating material. This terminal board carries four terminal posts 101, 102, 103, and 104 disposed at the four corners of a rectangle, which terminal posts, in turn, carry contact fingers 105, 106, 107, and 108, respectively. The two contact fingers 105 and 106 are shorter than the two contact fingers 107 and 108, and cooperate with a contact ring 109 mounted on an insulating rod 110, to form a contact 105—109—106. The rod 110 is secured to the head 93 of the biasing device, and also carries a contact button 111 which cooperates with the fingers 107 and 108 to form a contact 107—111—108. The parts are so proportioned that the contact 105—109—106 will be closed when the operating member 85 and associated parts occupy the positions shown, their right-hand extreme position, or any position intermediate these two positions, but will become opened when the operating member and associated parts are moved to their left-hand extreme position; and that the contact 107—111—108 will become closed when and only when the operating member and associated parts are moved to their right-hand extreme positions. The right-hand extreme position of the operating member and associated parts is limited by engagement of the extension 89^a of the light unit housing 89 with the left-hand end of the spring housing 82^e, and the other extreme position of the operating member and associated parts is limited by engagement of the left-hand end of the light unit housing with the front plate 82.

The operation of the circuit controller shown in Figs. 7 and 8, as a whole will be apparent from the foregoing description and from an inspection of the drawings without further detailed description.

Referring now to Fig. 12, the circuit controller here shown comprises, in general, an operating rod 120 mounted in a supporting bracket 121, and cooperating with contacts carried by the supporting bracket. The supporting bracket 121 may have any suitable form, but, in the form here shown, this bracket comprises a single strip of steel or other suitable material bent to form two spaced vertical portions 121^a and 121^b, and an intermediate connecting portion 121^c. The vertical portion 121^b is provided with a screw-threaded hole 121^e through which the right-hand end of the opening rod 120 extends with considerable clearance, and the vertical portion 121^a is provided with a threaded hole 121^f through which the left-hand end of the operating rod extends with considerable clearance. A bushing 123 is screwed into the hole 121^f, and this bushing serves both as a bearing for the operating rod, and as a means for fastening the circuit controller to the control panel 56. The bracket 121 is maintained

in the desired position with respect to the panel 56 by means of a dowel pin 122 which is riveted to the panel, and which projects into a clearance hole provided in the vertical portion 121^a of the bracket 121. The left-hand end of the operating rod is provided with a screw-threaded portion 120^a of reduced diameter which receives an operating button 124. The inner end of the operating button 124 is recessed for the reception of a lock washer 125 which serves to lock the button in place on the operating rod.

The operating rod is operatively connected with a biasing device D³ which in the form here shown comprises a tubular housing 126, the right-hand end of which is screwed through the opening 121^e in the bracket 121 and is locked in place by means of an end cap 127 provided with an opening 127^a. The left-hand end of the housing 126 is partly closed by an inwardly extending flange 126^a which forms an opening 126^b that aligns with the opening 127^a in the end cap 127, and slidably mounted in the openings 126^b and 127^a are sleeves 128 and 129, respectively, provided with annular flanges 128^a and 129^a located within the housing. The operating rod extends through the sleeves 128 and 129 with some clearance and is surrounded by a compression spring 130 which engages the sleeves at their annular flanges and urges them to the positions in which the annular flange 128^a on the sleeve 128 engages the flange 126^a on the housing 126, and the annular flange 129^a on the sleeve 129 engages a shoulder formed on the inside of the end cap 127. The operating rod is provided at its extreme right-hand end with a nut 131 for at times engaging the outer end of the sleeve 129, and with a jam nut 132 for locking the nut 131 in place. The outer end of the sleeve 128 cooperates with an insulating cam 133 which is pinned to the operating rod for operating the contacts of the circuit controller. The operation of the biasing device D³ will be apparent from an inspection of the drawings, and from the foregoing description of the operation of the other biasing devices shown in the preceding views, and need not, therefore, be described in detail herein.

The contacts of the circuit controller are arranged in a stack and are secured to a horizontal extension 121^d of the bracket 121 by means of screws 143. The extension carries a plurality of superposed blocks 134^a, 134^b, etc., of insulating material, and clamped between the blocks 134^a and 134^b is a first movable contact finger 135, the outer or free end of which is provided with a return bend 135^a which cooperates with the cam 133. A fixed contact finger 136 is clamped between the blocks 134^b and 134^c, and is retained in its normal position by a relatively stiff metal stop 137 which is also clamped between the blocks 134^b and 134^c. A similar fixed contact finger 138 and a stop 139 which is arranged to limit the upward movement of the finger 138 is also clamped between the blocks 134^b and 134^c. A second movable contact finger 140 is clamped between the blocks 134^c and 134^d, and the free end of this finger is bent downwardly and is provided with a return bend 140^a which also cooperates with a cam 133. The movable finger 135 cooperates with the fixed finger 136 to form a contact 135—136, and the movable finger 140 cooperates with the fixed contact finger 138 to form a contact 138—140. The fingers are so adjusted that when no force is being exerted on the movable fingers, the finger 135 will move due to its inherent bias to the position in which the contact 135—136 is

open, and the finger 140 will move due to its inherent bias to the position in which the contact 138—140 is closed.

The cam 133 is provided with oppositely inclined cam faces 133^a and 133^b, and the parts are so proportioned that when the operating rod 129 occupies the position to which it is biased by the biasing device D³, the cam 133 will be out of engagement with both movable contact fingers, but that, when the operating rod is moved inwardly to its one extreme position, the cam face 133^b will engage the return bend 135^a of the finger 135 and thus force the finger 135 upwardly to the position in which the contact 135—136 becomes closed, and that, when the operating rod is pulled outwardly to its other extreme position, the inclined face 133^a of the cam will engage the return bend 140^a on the finger 140 and force it upwardly to the position in which the contact 138—140 is open. The inner extreme position to which the operating rod can be moved is limited by engagement of the cam 133 with the right-hand end of the housing 126, and the other extreme position to which the operating rod can be pulled is limited by engagement of the cam 133 with the inner end of the bushing 123.

Referring now to Fig. 13, the circuit controller here shown is a modification of that shown in Fig. 12, and differs from that shown in Fig. 12 in that the vertical portions 121^a and 121^b of the bracket 121 are spaced somewhat farther apart and the biasing device which is here designated D⁴ instead of being mounted in a tubular housing secured to the leg 121^b of the bracket 121 is mounted in a U-shaped support 144 secured to the connecting portion 121^c of the bracket. Furthermore, the contacts of the circuit controller instead of being mounted on a horizontal extension of the bracket are mounted on an L-shaped insulating support 145 which is secured to the vertical leg of the bracket by means of screws 146. The operation of the circuit controller shown in Fig. 13 will be obvious from an inspection of the drawings.

Although I have herein shown and described only a few forms of circuit controllers embodying my invention, it is understood that various changes and modifications may be made therein within the scope of the appended claims without departing from the spirit and scope of my invention.

Having thus described my invention, what I claim is:

1. A circuit controller comprising a frame provided at its forward end with an opening, a tubular operating member slidably mounted in said opening, a light transmitting medium extending through said operating member, a housing secured to said operating member and containing indication lamps for at times illuminating said light transmitting medium, a plate secured to said housing, contacts secured to said frame, and cam means secured to said plate and cooperating with said contacts to selectively operate said contacts in accordance with the position of said operating member.

2. A detachable panel mounted circuit controller comprising, in combination, an L-shaped bracket having one leg thereof secured to the rear face of a control panel and provided with a hole which aligns with a hole in said panel, and a circuit controller supported by the other leg of said bracket and secured thereto at the rear end of the bracket, said circuit controller being provided at its forward end with a projecting

portion through which an operating member extends and which projects through the aligned holes in said bracket and said panel and acts as a dowel to position the forward end of said controller relative to said bracket and said panel.

3. An electric switch, comprising: switching elements, movable relatively to various positions; means for bodily moving at least one of said switching elements relative to the other in any one of the various positions; actuator means, having connection with said moving means, for effecting movement of said moving means, comprising an interior core of light transmitting material and an exterior surface opaque to light, said exterior surface being interrupted at spaced portions to expose said interior core; an electric lamp construction, so constructed and arranged that the electric lamp will be energized when said switching elements are in at least one predetermined position, the electric lamp being disposed adjacent one of said spaced portions, so that the light rays will be transmitted through the interior core to the other of said spaced portions.

4. A plural-position electric switch, comprising: actuator means, having connection with the switching elements of said electric switch for bodily moving at least one of the elements relative to the other in any one of the various positions, said actuator means being formed of glass, and the exterior surface of which is provided with an opaque covering, said covering being interrupted at spaced portions; and an electric lamp construction, so constructed and arranged that the electric lamp will be energized when said switch is in at least one predetermined position, the electric lamp construction being disposed adjacent one of said spaced portions, and the illumination being transmitted from said one portion through the glass of said actuator means to the other of said spaced portions.

5. An electric switch, comprising: switching elements, movable relatively to various positions; means for bodily moving at least one of said switching elements relative to the other in any of the various positions; tubular actuator means, having connection with said moving means, for effecting movement of said moving means; an electric lamp disposed exteriorly of and alongside said switch and so constructed and arranged that the electric lamp will be energized when said switching elements are in at least one predetermined position, said electric lamp construction being disposed adjacent one end of said tubular actuator means; and a glass core disposed within said tubular actuator means, constructed and arranged to transmit light from the electric lamp through the actuator means to the other end of said actuator means.

6. In combination: a mounting, having an aperture; an electric switch secured to said mounting at one side of said mounting; movable means, having connection with the switching element of said electric switch; an electric lamp construction, carried by said movable means and connected to a source of electrical energy; tubular actuator means, extending through said mounting aperture, and having connection with said movable means, for effecting movement of said movable means and said lamp construction, said actuator means having one open end disposed adjacent said electric lamp construction, on said one side of said mounting, and its other open end disposed on the opposite side of said mounting; and means constructed and arranged to cause

energization of the electric lamp when said electric switch is moved to a predetermined position, at least a portion of the light provided by the energized electric lamp entering said one open end of said actuator means and being directed to said other open end.

7. In combination: a mounting, having an aperture; an electric switch secured to said mounting at one side of said mounting; movable means, having connection with the switching element of said electric switch; an electric lamp construction, carried by said movable means and connected to a source of electrical energy; tubular actuator means, extending through said mounting aperture, and having connection with said movable means, for effecting movement of said movable means and said lamp construction, said actuator means having one open end disposed adjacent said electric lamp construction, on said one side of said mounting, and its other open end disposed on the opposite side of said mounting; means constructed and arranged to cause energization of the electric lamp when said electric switch is moved to a predetermined position; and means directing the light provided by the energized electric lamp, so that this light enters said one open end of said actuator means and is visible at said other open end, thereby visibly indicating at said opposite side of said mounting when said switch has been moved to said predetermined position.

8. In combination: a mounting, having an aperture; an electric switch secured to said mounting at one side of said mounting; movable means, having connection with the switching element of said electric switch; an electric lamp construction, positioned adjacent said switch, and being connected to a source of electrical energy; hood means, generally enclosing the electric lamp; tubular actuator means, extending through said mounting aperture, and having connection with said movable means, for effecting movement of said movable means and said lamp construction, said actuator means having one open end communicating with the interior of said hood means, and its other open end disposed on the opposite side of said mounting; and means constructed and arranged to energize the electric lamp when said electric switch is moved to a predetermined position, said hood means directing the light provided by the energized electric lamp to enter said one open end of said actuator means, so that this light is visible at said other open end, thereby visibly indicating at said opposite side of said mounting when said switch has been moved to said predetermined position.

9. In combination: a mounting, having an aperture; an electric switch secured to said mounting at one side of said mounting; movable means, disposed on said one side of said mounting, and having connection with the switching element of said electric switch; an electric lamp construction, connected to a source of electrical energy; hood means, generally enclosing the electric lamp, said electric lamp construction and said hood means being secured to and movable with said movable means; tubular actuator means, extending through said mounting aperture, and having connection with said movable means, for effecting movement of said movable

means, said actuator means having one open end extending into said hood means, and its other open end disposed on the opposite side of said mounting; and means constructed and arranged to energize the electric lamp when said electric switch is moved to a predetermined position, said one open end of said actuator means providing for the escape of light from said hood means, so that the light is directed toward said other open end, thereby visibly indicating at said opposite side of said mounting when said switch has been moved to said predetermined position.

10. In combination: a mounting, having an aperture; an electric switch secured to said mounting at one side of said mounting; movable means, disposed on said one side of said mounting, and having connection with the switching element of said electric switch; an electric lamp construction, connected to a source of electrical energy; hood means, generally enclosing the electric lamp, said electric lamp construction and said hood means being carried by said movable means; tubular actuator means, extending through said mounting aperture, and having a readily detachable connection with said movable means, for effecting movement of said movable means, said actuator means having one open end extending into said hood means, and its other open end disposed on the opposite side of said mounting; and means constructed and arranged to energize the electric lamp when said electric switch is moved to a predetermined position, the light from the electric lamp being confined within said hood means, and escapes only through said one open end of said actuator means and to said other open end, so as to visibly indicate at the opposite side of said mounting when said switch has been moved to said predetermined position.

11. In combination; a mounting member having a relatively small cylindrical passageway extending therethrough; a relatively small tubular sleeve extending through said cylindrical passageway and movable therein, a hollow knob secured to said sleeve at one end, a lens in the knob; a bracket secured to said mounting member, a lamp socket fastened to said bracket at the other end of said sleeve, a plurality of differently colored lamps in the socket; and a transparent rod extending through said sleeve for transmitting the light from said lamps to said lens.

12. In combination, a fixed mounting member extending from front to rear and having a relatively small cylindrical opening therein, a relatively slender tubular member movably fitted through said cylindrical opening, a knob mounted on said tubular member at one end, a transparent rod extending from said knob through said tubular member, an enlarged receiver at the other end of the tubular member, a plurality of electric lamps mounted in the receiver, energizing circuits for the lamps, and each positioned, when energized, to illuminate the rear end of said transparent rod, whereby the light from any lamp is transmitted to illuminate said knob and a plurality of lamps can be employed to illuminate said knob without increasing the size of the contact carrying structure for receiving the lamps and the lead in wires therefor.

WILLIAM E. SMITH.
